UNITED STATES PATENT OFFICE

133,775

DESIGN FOR A LAWN MOWER

Richard D. Clemson, Middletown, N. Y., assignor
to Clemson Bros., Inc., Middletown, N. Y., a
corporation of New York

Application July 6, 1942, Serial No. 107,432

Term of patent 14 years

To all whom it may concern:

Be it known that I, Richard D. Clemson, a citizen of the United States, residing at Middletown, New York, have invented a new, original, and ornamental Design for a Lawn Mower, of which the following is a specification, reference being had to the accompanying drawings, which form a part thereof, in which:

Fig. 1 is a perspective view taken from behind and to the right of a lawn mower showing my new design;

Fig. 2 is a perspective view taken from in front and to the left of the mower on an enlarged scale and with the handle partly broken away;

Fig. 3 is a perspective view from the rear similar to Fig. 1, but at a somewhat different

angle, on the same scale as Figure 2 with a part of the handle broken away;

Fig. 4 is a view from the rear of the mower with the handle in vertical position;

Fig. 5 is a view of the mower from above with a part of the handle broken away and on substantially the same scale as Figure 1; and

Fig. 6 is a view of one wheel partly in section and on an enlarged scale.

This application is a continuation-in-part of my prior co-pending application, Serial No. D76,105, filed March 26, 1938.

I claim:

The ornamental design for a lawn mower, substantially as shown and described.

RICHARD D. CLEMSON.
